ABRADING TOOL

Arthur S. Johnson, Beverly, Mass., assignor to
United Shoe Machinery Corporation, Paterson, N. J., a corporation of New Jersey

Original application December 11, 1931, Serial
No. 580,388, now Patent No. 2,032,418, dated
March 3, 1936. Divided and this application
July 11, 1935, Serial No. 30,849

3 Claims. (Cl. 51—194)

This invention relates to abrading tools and is
herein disclosed as embodied in an abrading roll
having a yieldable periphery. The illustrated roll
may be used for operations in which the work is
5 presented by hand, such as the scouring of shoe
bottoms, or the roll may be used to perform scouring,
buffing or similar operations upon pieces of
sheet material in a machine of the type illus-
trated in United States Letters Patent No.
10 2,032,418, granted March 3, 1936 upon my applica-
tion, of which this application is a division.

It is an object of the present invention to pro-
vide an improved abrading tool which may yield
readily to conform itself to the exact shape of
15 the work piece. The abrading element of the illus-
trated roll consists of a sheet of abrasive mate-
rial such as sandpaper or emery cloth which is
more or less stiff because of the glue employed
20 to retain the grit. The sheet of abrasive material
is supported by a yieldable cushion which con-
stitutes the peripheral portion of the roll body.
In accordance with a feature of the invention
the illustrated abrasive sheet material has formed
25 in it a plurality of pairs of parallel slits, the
slits of each pair being connected by a cut to form
a tab. As illustrated, the parallel slits of each
pair are so directed as to be circumferential with
relation to the roll upon which the abrasive sheet
30 is mounted. The tabs which are thus formed
tend to swing outwardly under the influence of
centrifugal force as the roll rotates and thereby
act yieldingly upon the work.

The several features of the invention will now
be set forth in connection with an illustrated ma-
35 chine and pointed out in the appended claims.

In the drawing.

The figure is a perspective view of the improved
abrading roll.

The roll illustrated in the figure is of the two-
40 part hinged type having a pair of collars 10 at
its ends for opening and closing the roll when
the abrasive cover is to be replaced. The periph-
eral portion of the roll body consists of a cushion
12 which in the illustrated construction consists
45 of sponge rubber. The abrasive cover for the
roll consists of a sheet of emery cloth 14 which

is secured in the usual way upon the periphery
of the roll body and which has formed in it a
plurality of slits 16 extending circumferentially
and arranged in parallel pairs, each pair being
connected by a cut 18 which runs longitudinally 5
of the roll. As a result of the above-mentioned
circumferential slits and parallel cuts there is
formed in the abrasive cover a plurality of tabs
20. Not only are the tabs 20 free to flex accord-
ing to the curvature of the work piece but also
the portions of the abrasive cover 14 between
the tabs will, by reason of the slits 16 and the
yielding cushion 12, be enabled to twist one way
or the other to accommodate the varying con-
tours of the work piece as the work piece is 10
pressed against the abrasive cover. The abra-
sive cover 14 is so arranged upon the roll with re-
spect to the direction of rotation, as indicated
by the arrow in the figure, that the free ends of
the tabs 20 will be the trailing ends. The tabs 20
will then swing outwardly under the influence of
centrifugal force and thus bear yieldingly upon
the work. The tabs of the illustrated abrasive
cover are arranged in parallel rows extending 15
lengthwise of the roll, with the tabs of each row
25 staggered with relation to the tabs of the next
row.

Having thus described my invention, what I
claim as new and desire to secure by Letters Pat-
ent of the United States is:

1. An abrading roll comprising a roll body hav-
ing a yieldable periphery and a cover of abrasive
sheet material secured upon said roll body, said
cover having formed in it a plurality of pairs
35 of slits directed circumferentially of the roll body,
the slits of each of said pairs being connected
by a cut extending lengthwise of the roll body to
form a tab.

2. A piece of abrasive sheet material having
formed in it a plurality of rows of tabs. 40

3. A piece of abrasive sheet material having
formed in it a plurality of pairs of parallel slits,
each pair of slits being connected by a cut to
form a tab.

ARTHUR S. JOHNSON. 45
